DISPENSING DEVICE FOR MULTIPLE CYLINDRICAL SLUGS OF AIR TREATING GEL

Charles B. Wenner, Darien, Conn., and Aurelio Dello Russo, Bronx, N.Y., assignors to Airkem, Inc., New York, N.Y., a corporation of New York

Filed Oct. 17, 1957, Ser. No. 690,795

10 Claims. (Cl. 239—35)

This invention relates to a vaporizing dispenser for air treating gels, and the like, adapted for mounting on a wall or other vertical support. More particularly, the invention relates to a dispenser of the class described providing storage for a plurality of bodies of air treating gel in a manner to introduce them individually into an evaporation chamber having controllable means for circulation of air therethrough, and wherein indicator means is provided to signal when the last stored body of gel has been transferred to said vaporization chamber.

In the introduction of volatile air treating agents into air, superior results are obtained when employing an air treating formulation in solidified or gel form. Such air treating gels have been disclosed in United States Patent No. 2,691,615. It has also been found, as disclosed in United States Patent No. 2,733,956 granted to one of the present applicants, that superior performance in introducing air treating agents into air from a gel type of product, is obtained when the gel is employed in the form of elongated cylindrical bodies supported horizontally in a storage chamber to drop individually through a restricted opening to a volatilization or vaporization chamber. The restricted passage between storage chamber and volatilization chamber serves to support the stored gel slugs until the lowermost gel slug has become shrunk or reduced in size due to emission of volatilizable material from the exposed surface thereof sufficiently to permit its passage through the restricted opening.

The present invention is concerned with a new and improved type of dispenser for air treating gels, and the like, embodying the basic principles of drop-through feed of gel slugs from a storage chamber to a volatilization chamber as above mentioned, but wherein the device embodies unique features providing for use as a relatively tamper-proof wall dispenser which can be adjusted to provide suitable or desired volatilization rates, and which also provides means, by external examination, to ascertain whether the device is in need of a fresh supply of gel slugs.

Novel features of the invention will readily be apparent from a consideration of the following description taken together with the accompanying drawing in which various parts of the device are identified by suitable reference characters in each of the views, and in which:

Fig. 1 is a front elevation view of the device;

Fig. 2 is an enlarged vertical section substantially on the line 2—2 of Fig. 1;

Fig. 3 is a rear view of the mounting plate portion of the device as shown in Fig. 2, seen in the direction of the arrows 3—3;

Fig. 4 is a fragmentary view of the assemblage shown in Fig. 2, substantially along the line 4—4 as seen in Fig. 3;

Fig. 5 is a fragmentary view of the assemblage shown in Fig. 2, taken substantially along the line 5—5 of Fig. 3; and

Fig. 6 is a fragmentary view of the assemblage shown in Fig. 2, taken substantially on the line 6—6 of Fig. 3.

2

The wall dispenser as shown in the drawing is of simple and practical construction embodying six readily formed and easily assembled parts, which can be fashioned from various materials, but which are particularly adapted for molding from various plastic materials. Preferably the device comprises an outer casing part 10 having close peripheral engagement with a mounting plate 11, and readily attachable and detachable with respect thereto as hereinafter described. The mounting plate 11 in turn carries a gel holder 12 defining an upper storage chamber 13 for cylindrical bodies 14 of air treating gel, and a basket member 15 for receiving partially spent bodies of gel 14' in a volatilization zone or chamber 16.

As seen in Fig. 1 of the drawing, the side walls 17 of the casing 10, as well as the top wall 18, and bottom wall 19 thereof, are tapered outwardly in a manner to provide a smooth, attractive appearance in the device while at the same time facilitating molding thereof. In this connection, it will be noted that side openings 20 in the casing or cover part 10 providing circulation of air to the volatilization chamber 16 can, by reason of the outward taper of the side wall 17, be fashioned by protruding members of a mold part employed to form the outer surface of the casing or cover 10.

25 The front wall 21 tapers outwardly from top to bottom as seen in Fig. 2 of the drawing at an angle substantially parallel to an inwardly protruding inclined surface 22 on the mounting plate 11. The spacing of the front wall 21, and inclined surface 22, provide in the chamber 13 30 a dimension closely conforming to the diameter of cylindrical gel slugs 14 for which the device is intended. In alignment with the volatilization chamber 16, the front wall 21 has an inwardly offset portion 23 provided with apertures 24 leading to the volatilization chamber 16.

35 The bottom wall 19 of the cover part has a central recess 25 providing a space within the general boundary of the device for viewing a signal element as will be hereinafter described. Attachment and detachment of the cover 10 with respect to the mounting plate 11 is 40 provided by an unique hinge-type coupling at the bottom portion of the device in the form of a pair of convex bearing members 26 at opposed inner sides of the bottom wall 19, engaging corresponding concave bearing members 27 at opposed lower corners of the mounting plate 11, as seen particularly in Fig. 4 of the drawing. It will be noted that abutting surfaces of the bearing members 26 and 27 are in engagement through an arc, or partial 45 cylindrical curvature of approximately 90°, and are located upwardly and forwardly of the center of curvature thereof. It will be evident that after limited outward tilting movement of the outer casing part 10, the outer casing part can be disengaged from the mounting plate 11 by slight downward movement to separate the bearing surfaces 26, 27.

55 When the outer casing part 10 is in the position shown in Fig. 2, having close peripheral engagement with the mounting plate 11, it will be evident that the interengagement between bearing surfaces 26 and 27 forms a positive lock preventing outward movement of the lower end 60 of the casing 10. The upper end of the casing 10 is secured to the base plate by a lock element 28 protruding forwardly of the base plate, and engaging detent means 29 in the top wall 18 of the casing. A slit or aperture 30 is provided in the top wall 18 in alignment with the lock member 28 to permit insertion of a suitably shaped key, or the like, in order to depress the lock member 28 when it is desired to remove the outer casing 10. The aperture 30 can be shaped to receive any sharp instrument, or if desired, can be specially shaped to receive a 65 particular type of insertable key, thus rendering the device more fully tamper-proof.

The mounting plate 11 has at the lower extremity of

the inclined wall 22, and at opposed end portions thereof, elongated slits or apertures 31, note Figs. 3 and 5 of the drawing. The gel holder 12 is provided with rearwardly extending tongues 32 adapted to engage the apertures 31, and being contoured to provide an upwardly extending bearing means 33 engaging the back side of the inclined wall portion 22, and a recessed or cut-out portion providing a shoulder 34 bearing against the outer surface of the inclined wall 22 as seen in Fig. 5 of the drawing. This type of engagement provides for easy assemblage of the parts which, if desired, may be cemented or otherwise bonded in assembled position. On the other hand, the gel holder 12 may remain as a detachable part facilitating periodic removal or cleaning, and the like.

The front wall portion 12a of the gel holder is substantially inclined as seen in Figs. 2 and 5 of the drawing to provide between the lower edge of the wall 12a and the lower edge of the wall 22, a restricted spacing or clearance approximately three-fourths the diameter of gel slugs 14 to be used in the device. If the size of gel slug is to be substantially varied, it will be evident that the gel holder 12 can be readily removed, and replaced by a gel holder of appropriately modified size to accommodate the different sized gel slugs.

The basket member 15 is provided intermediate its ends with downwardly extending reinforcing ribs 35 terminating at their rear end portions in bearing surfaces 36 for engagement with the lower end portion of the mounting plate 11. The ribs 35 also carry rearwardly protruding hook-like members 38 which pass through apertures 39 in the mounting plate 11, note Figs. 3 and 6 of the drawing. It will readily be apparent that this engagement between the basket member 15, and the mounting plate 11 provides for easy attachment and detachment of the basket 15 when the cover or casing 10 is removed from the mounting plate.

Inner side walls of the casing part 10 are provided with slotted guides 40 (note Fig. 2 of the drawing) which slidably receive adjustable barrier means 41 when it is desired to diminish the amount of circulation through the air passages 20. The barrier means can suitably be in the form of a thin sheet of cardboard, metal, or plastic, and adjustment in the amount of circulation through the air passages 20 can be effected either by movement or adjustment of the barrier means 41, or by employing interchangeable barrier members 41 of different size. In this connection, it will be apparent that normally such adjustment in the effective size of the air passages 20 need be made only when initially setting up the wall dispenser in a particular environment having reference to the size of the space to be treated, and the type and amount of air treatment desired.

When the dispensing device is initially loaded with a full gel slug resting in the basket member 15, and two gel slugs supported by the gel holder 12, the device can be expected to operate continuously and unattended for an extended period of time, and even after evaporation and shrinkage of gel slugs has permitted the last gel slug to drop from the gel holder 12, there will be considerable effective evaporation from the device. At the same time, when there are no longer gel slugs supported by the gel holder, it is time for replenishing the supply of gel and removing spent gel slugs from the basket 15.

The device as shown in the drawing includes signal means visually indicating to an attendant externally of the device, whether or not gel slugs remain supported on the gel holder 12. This signal means, as shown in Figs. 2 and 3 of the drawing, comprises a flat plate member 42 seated against a rearwardly offset portion 43 of the base plate 11, the front surface of the plate member 42 being normally in alignment with the front surface of the inclined wall 22, and engageable by a gel slug resting in the gel holder 12. The upper end of the plate member 42 carries spaced rearwardly extending hooks 44 which engage protruding lugs 45 on the offset member

43 in a manner to provide swinging movement of the plate member 42. Above the hooks 44, and extending the full length of the plate 42, is a rearwardly extending flange 46 apertured as at 47 to receive a hook 48 at the upper extremity of a vertically movable signal rod 49. Thus, as the plate 42 pivotally moves about the axis provided by the hooks 44 and lugs 45, a vertical reciprocating movement is imparted to the rod 49.

The rod 49 as seen in Fig. 3 of the drawing, passes through a channel 50 provided between reinforcing members 51 of the mounting plate 11. A slight enlargement 52 is provided in the rod 49 to closely, but slidably engage walls of the channel 50. The lower extremity of the rod 49 carries a signal element 53 which is shown in Figs. 2 and 3 of the drawing in the retracted position. When no gel slug is on the gel holder 12, however, the plate 42 will swing outwardly, and the signal element 53 will move downwardly, occupying the position shown in dot-and-dash lines in Fig. 1 of the drawing. In order to limit downward movement of the rod 49, and signal element 53, the rod 49 is provided with laterally protruding lugs 54, suitably spaced from the reinforcing members 51 on the mounting plate 11, so that bearing stop engagement is provided between the lugs 54, and the reinforcing members 51 at the desired downward protrusion of the signal element 53. When the device is refilled with fresh gel slugs, it will be apparent that the placing of a gel slug on the gel holder 12 will pivot the plate 42 into alignment with the inclined wall 22, and thereby retract the signal element 53 to inoperative position.

For purpose of illustration, the apertures 55 have been shown in the mounting plate to facilitate attachment of the device to a wall or vertical support by means of screws or other suitable fasteners. It is to be understood, however, that any type of permanent or detachable mounting of the device on a vertical support can be employed.

While the upper storage chamber 13 has been shown as providing for storage of two gel slugs 14 supported on the gel holder 12, it will be understood that the size of the chamber 13 can be increased if desired, to accommodate three, or even four gel slugs 14. It is not considered advisable, however, to support more than four gel slugs above the gel holder 12 in a device of the type shown, since excessive weight of stored gel slugs upon the lowermost slug 14 may force said gel slug prematurely through the restricted opening provided by the gel holder 12, thus alternating the intended performance of the device, particularly with respect to the rate of emission of volatilizable materials therefrom. The preferred adaptation of the device employs a storage chamber 13 to receive two gel slugs as shown in the drawing.

Various changes and modifications in the diffusing device herein disclosed will occur to those skilled in the art, and to the extent that such changes and modifications are embraced by the appended claims, it is to be understood that they constitute part of our invention.

We claim:

1. A wall type diffusing device for air treating gel in cylindrical slug form, said device comprising a vertically disposed mounting plate, a casing part having a front wall and integral top, bottom, and opposed side walls providing close peripheral engagement with said mounting plate, cooperating means on said mounting plate and casing at upper and lower edge portions thereof for detachably securing the casing to said mounting plate, horizontally disposed gel support means protruding outwardly from said mounting plate dividing the space between said mounting plate and casing into an upper storage chamber and a lower volatilization chamber, walls of said casing below said gel support having apertures providing free circulation of air therethrough, and basket means 70 protruding outwardly of said mounting plate at the lower

portion thereof for supporting bodies of air treating gel in alignment with said apertures.

2. A wall type diffusing device as defined in claim 1 wherein the gel support and basket means comprise parts detachably coupled with said mounting plate.

3. A wall type diffusing device as defined in claim 1 wherein the mounting plate above said gel support is slightly inclined rearwardly, whereby a plurality of cylindrical gel slugs can be retained by said gel support without contacting said casing.

4. A wall type diffusing device as defined in claim 3 wherein the inclined portion of said mounting plate includes a pivotally movable panel adjacent said gel support adapted to swing outwardly when no gel slug is on said support, and said pivotally movable panel being coupled with a signal element visible externally of said device when the panel is in its outwardly pivoted position.

5. A wall type diffusing device as defined in claim 4 wherein said signal element is a vertically reciprocating member at the rear of said mounting plate having an enlarged lower end normally concealed by said mounting plate and protruding to visible position when lowered by the outward swinging movement of said panel.

6. A wall type diffusing device as defined in claim 5 wherein the rear surface of said mounting plate includes guide means for said reciprocating member, and protruding portions of said vertically reciprocating member engage said guide means to limit downward movement of said signal element.

7. A wall type diffusing device as defined in claim 1 wherein the means for detachably securing said casing to said mounting plate includes a spring lock on said mounting plate engaging detent means at the upper portion of said casing, and undercut means at the lower portion of said mounting plate interfitting with upwardly protruding means at the lower portion of said casing.

8. A wall type diffusing device as defined in claim 7 wherein said interfitting means comprises a convex bearing on said casing and a concave bearing on said mounting plate of substantially quarter-cylindrical contour disposed above and forwardly of the axis of cylindrical curvature, whereby engagement and disengagement of the casing with respect to said mounting plate is possible only when the top of said casing is in an outwardly swung position with respect to said mounting plate.

10. 9. A wall type diffusing device as defined in claim 1 wherein inner side walls of said casing are provided with horizontally disposed channel members above and below apertures in said side walls for detachably and adjustably receiving baffle means restricting the effective size of said apertures.

10. 10. A wall type diffusing device as defined in claim 9 wherein the upper of said channel members are in substantial alignment with the lower portion of said gel support, and said gel support is in the form of a three-sided loop detachably coupled with said mounting plate, the ends of said three-sided loop being spaced apart to receive the length of a predetermined cylindrical gel slug, and the side of said loop opposed to said mounting plate being inclined sufficiently and spaced from said mounting plate to support a fresh gel slug with the lowermost portion thereof above the bottom of said gel support.
